(74) Attorney, Agent, or Firm — QuickPatents, LLC;
Kevin Prince(57) **CLAIM**

The ornamental design for a whisk, as shown and described.

DESCRIPTION

FIG. 1 is a bottom perspective view of a whisk, showing my new design;

FIG. 2 is a front elevational view thereof, the rear elevational view being a mirror image thereof;

FIG. 3 is a left-side elevational view thereof, the right-side elevational view being a mirror image thereof;

FIG. 4 is a top plan view thereof;

FIG. 5 is a bottom plan view thereof; and,

FIG. 6 is a top perspective view thereof.

The broken lines in FIG. 4 depict portions of the whisk that form no part of the claimed design.

1 Claim, 4 Drawing Sheets(56)
